US0D1015338S

(12) **United States Design Patent** (10) **Patent No.:** **US D1,015,338 S**
(45) **Date of Patent:** **** Feb. 20, 2024**

(54) **TELEVISION RECEIVER**

(71) Applicant: **Samsung Electronics Co., Ltd.**, Suwon-si (KR)
(72) Inventor: **Kyoosang Choi**, Suwon-si (KR)
(73) Assignee: **SAMSUNG ELECTRONICS CO., LTD.**, Gyeonggi-Do (KR)

(**) Term: **15 Years**

(21) Appl. No.: **29/844,121**

(22) Filed: **Jun. 27, 2022**

(30) **Foreign Application Priority Data**

Dec. 28, 2021 (KR) 30-2021-0062739

(57) **CLAIM**

The ornamental design for a television receiver, as shown and described.

DESCRIPTION

FIG. 1 is a front, top and right side perspective view of a television receiver, showing my new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof; and,

FIG. 8 is a rear, top and right side perspective view thereof. The even-dash broken lines illustrating portions of the television receiver form no part of the claimed design.

1 Claim, 7 Drawing Sheets
